UNITED STATES PATENT OFFICE.

ISIDORE SCHNEIDERMAN, OF BROOKLYN, NEW YORK.

RING CONSTRUCTION.

Application filed October 6, 1925. Serial No. 60,728.

To all whom it may concern:

Be it known that I, ISIDORE SCHNEIDERMAN, a citizen of Russia, residing at Brooklyn, Kings County, and State of New York, have 5 invented certain new and useful Improvements in Ring Construction, of which the following is a specification.

This invention relates to finger rings and more particularly to what is known in the 10 trade as dinner rings.

A particular object of the invention is to construct a ring having a hinged top piece which forms the cover for a compartment in the top of the ring, in which may be 15 placed a miniature watch or portrait.

A further object of the invention is to so construct the ring that the compartment in the top thereof will not be evident to one not familiar with its construction.

20 A further particular object of the invention is to provide a top for this type of ring which will be also a gem setting, that is, one in which the various gem setting will not interfere with the contents of the hollow 25 space or compartment in the upper part of the ring.

Referring to the drawing wherein I have shown a preferred embodiment of my invention;

30 Fig. 1 is a top plan view of a ring constructed in accordance with my invention;

Fig. 2 is a view thereof in side elevation showing the construction of the ring;

35 Fig. 3 is side view of the shank portion of the ring, the ends of the top piece being shown in outline;

Fig. 4 is an end view of the ring shank illustrated in Fig. 3;

40 Fig. 5 is a view in transverse section through the bezel, the top view of which is seen in Fig. 1, the bottom plate being also shown in this view to show how it fits on the bezel to form a bottom for the same;

45 Fig. 6 is a view in transverse section through the top or gem holding portion of the ring;

Fig. 7 is an enlarged sectional side view of the hinge portion of the ring, taken on line 7-7 of Fig. 1;

50 Fig. 8 is an enlarged section side view of the latch portion of the ring taken on line 8-8 of Fig. 1.

Fig. 9 is a cross section taken through the center of the ring showing how the chamber formed by the top of the ring can be used to hold an article, a watch being shown in

place it being understood that a portrait or other useful or ornamental article could be used as well.

Referring to the drawing in detail, the 60 method of constructing the ring will first be explained. The ring consists of the finger band or shank 5 to the upper ends 6 of which is soldered the bezel 7 which is constructed in any desired band shape and provided on its upper edge with spaced up-standing prongs 9. On this bezel is placed the top 10 or gem holding portion of the ring which may be dome shaped, it being understood that the showing in the drawing 70 being for the purpose of illustration only. The lower edge 11 of the top 10 is soldered to the ends of the prongs 9 and the ends 12 of the top where they extend down over the upper ends of the shank 5 are soldered there-to as at 13 as partly shown in Fig. 3 in outline.

A solid bottom piece or plate 14 having the same shape as the bezel is then placed on the bottom of the bezel and soldered in place 80 as shown in outline against the bezel in Fig. 5.

The ends 12 of the top and also the prongs 9 of the ring are then cut across, so that the shank if seen alone would have the appearance as shown in Fig. 3, the end of the shank inside the ends 12 forming a shoulder on which rests the ends of the bezel 7. On one end of the top end 12 I provide, by soldering, a hinge piece 15 which is adapted to be bent through a small opening 16 formed in the lower side end of the top 10 adjacent the point where it has been cut free as above described. This provides a hinge upon 90 which the top piece may be swung open when released at the opposite side by the resilient catch 17 which is soldered to the inner side of the adjacent top end 12, this catch comprising a finger portion 18 and a catch hook 19, the latter extending through an opening 20 in the top of the ring while the portion 18 extends through an opening 21 in the adjacent top end 12. The latch being resilient and having a tendency to move outwardly will normally hold the top of the ring closed. When the catch however, is released the top will be swung open by a small spring piece 22 which is soldered 100 against the top end 12 which is adjacent the hinge 15.

The top of the ring is of course suitably engraved, decorated or pierced and provided

in its top with a gem holding arrangement as is usual.

It is evident that the top being dome shaped, forms a chamber or receptacle into which may be placed any desired ornament, portrait, watch or the like, there being shown in Figure 9, a watch for illustration.

It will be evident therefore that I have provided a novel ring construction and one which will not be any larger than the usual ring and which may be used to contain useful or ornamental articles as before mentioned.

Having described my invention what I claim is:

A finger ring construction comprising a shank, a hollow top piece having a slot at one end thereof, a reduced loop portion on the shank adapted to pass through the slot to form a hinge, and a spring latch at the opposite end for maintaining the ring in closed position.

In testimony whereof I hereunto affix my signature.

ISIDORE SCHNEIDERMAN.
